REAR GUN SIGHT

George E. Elliason, 16161 Middlebelt, Livonia, Mich.

Filed Aug. 22, 1960, Ser. No. 61,840

Term of patent 14 years

(Cl. D30—1)

FIG. 1 is a top plan view of a rear gun sight showing my new design;

FIG. 2 is a side elevational view thereof;

FIG. 3 is an end elevational view taken from the left of FIG. 2; and,

FIG. 4 is a perspective view thereof.

The undisclosed side of the gun sight is substantially the same in appearance as the side shown.

I claim:

The ornamental design for a rear gun sight, substantially as shown and described.
